UNITED STATES PATENT OFFICE.

ALFRED JAMES TOZER, OF WELLINGTON, NEW ZEALAND.

BOLT FOR USE IN CONJUNCTION WITH EXISTING DOOR LOCKS.

Application filed June 18, 1925, Serial No. 38,076, and in New Zealand June 18, 1924.

This invention relates to bolts employed for securing doors and the like in closed positions, and used in conjunction with cylindrical, or barrel locks, through the operation of which said bolts are shot into their sockets, and are withdrawn therefrom, to lock or to unlock, respectively the doors or the like.

The type of lock at present used with 10 cylindrical or barrel locks is unsatisfactory, in that in many cases it is possible by inserting a knife or other tool between the door and the jamb, or through the latter, to engage the bevelled portion of the bolt 15 in such a way, that said bolt can be forced against the action of its spring, to clear the socket, and so unlock the door.

The main object of the present invention is to provide a bolt which will give a greater 20 degree of security and safety than the type above mentioned, other objects being to provide a simple and comparatively inexpensive form of bolt capable of being adjusted for use in any of a plurality of positions, said 25 bolt also being provided with means for locking the door from the inside against persons not in possession of a key fitting the lock of the door, while the lock is at all 30 times capable of being operated by persons in possession of the right key.

According to the invention a pair of bolt members are slidable horizontally in a casing adapted to be secured to the inside of a door, the lower of said bolt members being 35 provided with a toothed portion or rack for meshing with a pinion in which the end of the operating bar or rod from the lock is engaged, so that upon said lock being operated by turning a key therein the pinion 40 is given turning movement and either shoots the lower bolt member into its socket or withdraws it from the latter.

The upper bolt member is provided with a handle by means of which it may be 45 operated independently of the lower bolt member, either to lock or to unlock the door, or so as to be operated in conjunction with the lower bolt member when a key is used in the lock.

50 In the accompanying drawing, in conjunction with which the invention will be further described.

Figure 1 is a part sectional plan view showing a lock and a bolt fitted to a door,

55 Figure 2 is a front elevation of the bolt and its casing,

Figure 3 is a rear elevation of the bolt and casing with portion of the back plate of the latter removed.

Figure 4 is a cross sectional view of the 60 bolt members taken on the line A—A, Figure 3, while,

Figure 5 is an elevation of the hand operating means provided with the upper bolt member.

A pair of bolt members 1 and 2 are 65 slideable horizontally in a casing 3 adapted to be secured by screws 3^a or the like to the inside of a door 5 at right angles to the axis of the cylinder or barrel lock 4 inserted in the door 5, the lower of said bolt members 1 and 2 being toothed or provided on its underside with a rack 6 with which meshes a toothed wheel or pinion 7 mounted in the casing 3, so that on turning movement being imparted to said toothed wheel or pinion 7 the lower bolt member 2 can be projected from the casing 3 and be engaged in a socket 9 in or on the door jamb 10 or be withdrawn from said socket 9, as may be 70 required.

The toothed wheel or pinion 7 contains a cross slot or recess 22 into which the end of the operating bar or rod 11 from the barrel or cylinder of the lock 4 is entered, so that 75 upon a key which fits said lock 4 being inserted therein turning movement can be imparted through said bar or rod 11 to the toothed wheel or pinion 7 to cause the bolt member 2 to enter, or be withdrawn from 80 the socket 9 on or in the door jamb 10 as aforesaid.

The other or upper of said bolt members 1 and 2 is slideable on the toothed bolt member 2 either by hand and independently of 90 the latter, or with same, under the action of turning the key inserted in and fitting the lock 4.

The upper bolt member 1 contains a recess or cross slot 12 in its under side, and the 100 lower or toothed bolt member 2 has a pair of directly opposite cross recesses or slots 13 in its upper side, each of said last mentioned cross recesses or slots 13 extending from near the centre of the top of the bolt member 2 and opening through a side of the latter, said slots or recesses 13 deepening towards the sides of the bolt member 2 whereby there is provided between said slots or recesses 13 a ridged portion 14 on which an 105 arm or member 15 is entered in the cross slot or recess 12 in the upper bolt member 1,

said arm or member 15 being provided with a projection 16 which is entered in a recess 17 in the upper bolt member 1 to prevent said arm or member 15 from being withdrawn from the latter. The arm or member 15 mentioned is tapered at 15^a at its inner end to permit it to be rocked.

When the cross slot or recess 12 in the upper bolt member 1 registers with the cross slot or recess 13 in the lower bolt member 2, the arm or member 15 entered in the upper bolt member 1 also enters the cross slots or recesses 13 in the lower bolt member 2 and locks the two bolt members 1 and 2 together whereupon said bolt members 1 and 2 may be slid together in either direction either by inserting a key in the lock 4 and imparting turning movement to the toothed wheel or pinion 7 as aforesaid, or by moving said arm or member 15, the latter extending through a slot 18 in the front of the casing 3 and being provided with a knob or handle 19 to facilitate its being gripped and operated by hand.

When it is desired to use the upper bolt member 1 only, such as for instance, when it is desired to lock the door 5 from the inside and without using a key, the arm or member 15 entered in the upper bolt member 1 is lifted from engagement with the slots or recesses 13 in the lower or toothed bolt member 2, whereupon said upper bolt member 1 may be slid into engagement with the socket 9 in or on the door jamb 10. To unlock the door 5 when the latter is locked by the upper bolt member 1 the latter can either be slid by hand until it clears the socket 9, or the lower or toothed bolt member 2 may be operated from the outside of the door 5 by means of the key to cause it to move until the slots or recesses 12 and 13 in the bolt members 1 and 2 register with each other, whereupon the arm or member 15 in the upper bolt member 1 will drop and lock the two bolt members together, after which the latter can be moved or slid together out of engagement with the socket 9 by turning movement of the key.

The bolt members 1 and 2 are slideable in the casing 3 between upper and lower guides 20 and also between the slotted front of the casing 3, and a removable plate 21 dovetailed in the back of the latter.

The toothed wheel or pinion 7 is removably held in a cylindrical housing 7^a provided in the casing, said housing being open at one side to allow the teeth of the wheel or pinion 7 to mesh with the teeth of the bolt member 2.

The casing 3 is made with upper and lower housings 7^a for the toothed wheel or pinion 7 in order that either the top or bottom of the casing 3 may be used uppermost, the bolt members 1 and 2 being reversed top side for bottom side in the casing, so that the bolt member 1 is always on top. Also the bolt members 1 and 2 may be reversed end to end,

in the casing 3, to suit right and left handed doors.

The lower or toothed bolt member 2 is prevented from being slid out of the casing 3 by having its teeth 6 formed flush with its under side, while the upper bolt member 1 is prevented from leaving the casing 3 by the arm or member 15 projecting through and working in the slot 18 in the casing 3.

The bolt members 1 and 2 are made of 7^b such a length that they will enter more than the usual distance into the socket 9 and when operating said members by means of the key several turns of the latter are required to shoot the bolt member or members fully home into the socket 9 and to withdraw same from the latter.

By this means additional security is obtained, and there being no bevelled portions on the members 1 and 2 the latter cannot be 85 disengaged from the socket 9, in the manner earlier mentioned.

What I do claim and desire to obtain by Letters Patent of the United States of America is:—

1. Means for the purpose specified, comprising, a casing to be secured to the inside of a door, a toothed bolt slideable in the casing, a toothed wheel in mesh with the toothed bolt, a bar to operate the wheel and a lock 95 barrel in the outer side of the door connected to the bar for turning the bar and thereby operating the bolt, a seat in the toothed wheel to receive one end of the bar and upper and lower housings in the casing 100 for the toothed wheel.

2. Means for the purpose specified, comprising, a casing to be secured to the inside of a door, a toothed bolt slideable in the casing, a toothed wheel in mesh with the toothed bolt, a bar to operate the wheel and a lock barrel in the outer side of the door connected to the bar for turning the bar and thereby operating the bolt, and an upper bolt arranged to slide in the casing, either independently of, or together with, the toothed bolt, a recess in the upper bolt, an arm engaged in the recess, a recess in the toothed bolt, the arm being engageable in the toothed bolt recess for locking the bolt members together.

3. Means for the purpose specified, comprising, a casing to be secured to the inside of a door, a toothed bolt slideable in the casing, a toothed wheel in mesh with the toothed bolt, a bar to operate the wheel and a lock barrel in the outer side of the door connected to the bar for turning the bar and thereby operating the bolt, and an upper bolt arranged to slide in the casing, either independently of, or together with, the toothed bolt, a recess in the upper bolt, an arm engaged in the recess, a recess in the toothed bolt, the arm being engageable in the toothed bolt recess for locking the bolt members 130

together, the recess in the toothed bolt opening through one side thereof and deepening from the centre to the side thereof.

4. Means for the purpose specified, comprising, a casing to be secured to the inside of a door, a toothed bolt slideable in the casing, a toothed wheel in mesh with the toothed bolt, a bar to operate the wheel and a lock barrel in the outer side of the door connected to the bar for turning the bar and thereby operating the bolt, and an upper bolt arranged to slide in the casing, either independently of, or together with, the toothed bolt, a recess in the upper bolt, an arm engaged in the recess, a recess in the toothed bolt, the arm being engageable in the toothed bolt recess for locking the bolt members together, a pair of directly opposed recesses in the toothed bolt, each opening through one side of the bolt and deepening from the center to one side thereof, to provide a ridged portion on which the arm in the recess of the upper bolt can rest.

5. Means for the purpose specified, comprising, a casing to be secured to the inside 25 of a door, a toothed bolt slideable in the casing, a toothed wheel in mesh with the toothed bolt, a bar to operate the wheel and a lock barrel in the outer side of the door connected to the bar for turning the bar and 30 thereby operating the bolt, and an upper bolt arranged to slide in the casing, either independently of, or together with, the toothed bolt, a recess in the upper bolt, an arm engaged in the recess, a recess in the 35 toothed bolt, the arm being engageable in the toothed bolt recess for locking the bolt members together, a guide slot in the front of the casing through which the arm projects, the arm being tapered at its inner end, a pin on 40 the inner end of the arm, and an aperture within the recess in the upper bolt receiving the pin.

In testimony whereof I have signed my name to this specification.

ALFRED JAMES TOZER.
